UNITED STATES PATENT OFFICE

DANIEL B. DIMICK, OF BIRMINGHAM, ALABAMA

METHOD OF CASTING PIPE

Application filed October 23, 1929. Serial No. 401,767.

The present invention relates to improvements in method for the manufacture of cast iron lock joint culvert pipe, and has for an object the production of pipe of uniform thickness.

Another object of the invention is to provide an improved method and apparatus for the manufacture of cast iron culvert pipe having locking keys for effecting a lock joint between adjacent pipe sections in which a high degree of accuracy and uniformity in the size, thickness and other dimensions of the pipe and keys is had.

A further object of the invention is to provide an improved method and apparatus for the manufacture of cast iron culvert pipe in which a pipe having a uniform thickness of wall may be produced with a minimum expenditure of labor and power, and in which the capacity of the plant will be materially increased.

With the foregoing and other objects in view, the invention will be more particularly pointed out in the claims appended hereto.

In the drawings, wherein like symbols refer to like or corresponding parts throughout the several views,

Figure 1 is a top plan view of the empty flask, showing the component parts to make up said flask and their relation to one another, and with the spigot key chill members in place ready to receive the pattern.

Figure 2 is a vertical section taken on the line 2-2 in Figure 1 and with the pattern shown in place.

Figure 3 is a vertical central section of the complete flask mold with stripping plates in place ready for the pattern to be withdrawn.

Figure 4 is a vertical sectional view of the complete mold ready for bottom pouring of the pipe.

Figure 5 is also a vertical central section similar to Figure 4 modified in that the device is constructed for top pouring of the pipe.

Figure 6 is a front elevation, with parts broken away and parts shown in section of a machine for molding the combined bell core and pour basin.

Figure 7 is a view similar to Figure 6, but

with the bell core pattern keys drawn back into the mold stripping position and the completed combined bell core and pour basin mechanically stripped or lifted from the core box section of the machine, ready to be removed to its place in a flask mold.

Figure 8 is a vertical fragmentary section of the top portion of the flask mold with stripping plates in place and the pattern ready to be withdrawn and showing also the lifting mechanism used in withdrawing the pattern.

Figure 9 is a front elevation of the complete flask and pattern assembled on a pneumatic jarring machine.

Figure 10 is also a front elevation, with parts broken away and parts shown in section, of the complete flask and pattern assembled on a mechanically operated turntable ready for the molding sand to be thrown in place by means of a conventional sand thrower molding machine.

Figure 11 is a bottom plan of the improved runner box employed.

Figure 12 is a section taken on the line 12-12 in Figure 11.

Figure 13 is a section taken on the line 13-13 in Figure 11.

Figure 14 is a top plan view of the improved bell core box used showing also the bell core keys.

Figure 15 is a section taken on the line 15-15 in Figure 14 with the bell core keys removed, and

Figure 16 is also a sectional view taken on the line 16-16 in Figure 14.

Referring more particularly to the drawings 20 designates a casting stool, which constitutes the bottom of the flask. As shown in Figures 1 and 4 the casting stool may be provided with one or more pockets 21 therein to center and hold the bottom pour gate cores, when used. The casting stool 20 is also drilled to receive the cheek centering pins 22 and the arbor centering pins 23. The cheek is designated at 24 and constitutes the outside retaining wall of the flask, the same being machined to the length of the pipe mold desired. The cheek 24 is provided with a perforated flange 25 at its lower portion.

to receive the centering pins 22. These pins retain the cheek in proper concentric relation with the stool 20. The core arbor is designated at 26 and is provided with the per-
5 forated flange 27 to receive the centering pins 23. This arbor 26 is machined to the length of the straight bore of the pipe mold desired.

The pins 23 are located concentrically with
10 the center of the flask. The core arbor 26 may be provided with wings 28 to support and hold the molding sand in place in the core of the finished mold.

The pattern is shown at 29. This pattern
15 is constructed for the straight bore of the desired pipe and also for the outside of the bell of said pipe. The top portion of the pattern 29 is extended to receive means for withdrawing the pattern from the flask mold,
20 and for this purpose openings 30 are provided in the upper extended portion of the pattern. At 31 is shown cast iron spigot end taper locking key chills, the inside surface of each being formed to the radius of the
25 outside of the pattern. A cavity 32 is provided in the inner surface of each chill having the size and form of the desired spigot end taper locking key for its respective pipe pattern. The chills 31 are received into re-
30 cesses 33 provided in the sectional cast iron spigot key chill rings 34, which are securely attached to the casting stool as by the screws or bolts 35 in such manner and in such relation to the center of the flask as to hold the in-
35 side surfaces of the spigot key chills, and thereby the pattern 29, concentric with the flask.

The parts are such as to hold the spigot key chills 31 in place against the pressure of
40 the molding sand after the withdrawal of the pattern and for this purpose the upper edges of the chills 31 are sloped as indicated at 36 whereby to deflect the pressure of the sand outwardly.

45 Referring to Figures 3 and 8, 37 designates the outer stripping plate machined in bore to the outside diameter of the top or enlarged bell end of the pattern 29. The inside stripping plate is represented at 38. This inside stripping plate, is machined on its outer diameter to the bore of the pattern. A weighted or massive cast iron centering plug 39 rests upon the arbor 26 within the inner stripping ring or plate 38. The engaging surfaces of the plug 39 and stripping plate 38 are properly machined and the outside surface of the plug 39 is preferably tapered as shown. The outside stripping plate 37 is held in place by the use of clamps 40 in a well known manner. The tampered molding sand rammed in place between the pattern 29 and cheek 24 is represented at 41 and the sand between the pattern 29 and the arbor 26 is shown at 42. After the withdrawal of the

pattern, a mold cavity 43 is left in the sand, as shown in Figures 4 and 5.

As shown in Figure 4, 44 designates a pouring gate cavity made in the rammed molding sand as a restricted path for the molten iron to travel from the pour basin 45 to the casting stool core gate.

As shown in Figures 1 and 4, the lower end of this pouring gate cavity 44 communicates with one or more horizontal gate cavities 46 and similar connecting vertical cavities 47, which latter communicates with the lower end of the mold cavity 43. A runner box is shown in Figures 4 and 5 as being in place on the flask.

75 This runner box is also more particularly illustrated in Figures 11, 12 and 13. The runner box 48 may be a combination of cast iron and steel of such form as to support the tempered molding sand 49, when rammed to the shape and size desired to make a combined bell core and pour basin. At 50 are shown the impressions made in the bell core by the bell locking key patterns, leaving cavities of the size and in the positions desired for bell locking keys.

80 Referring to Figure 5, 51 designates the thin passage cavities molded into the combination bell core and pour basin, said passages leading from the pour basin 45 to the upper end of the mold cavity 43. This form is used where the molten metal is introduced to the upper end of the cavity 43.

85 The dry sand gate cores 52 are placed in the cavities or pockets 21 of the casting stool 20 whenever the molten metal is to be poured into the bottom of the mold cavity 43, as shown in Figure 4.

90 Now the runner box 48 and its core are prepared upon the machine shown in Figures 6 and 7. This machine includes in its construction a core box 53, which core box is more particularly shown in Figures 14, 15 and 16. The inside of the core box is machined to the size and shape of the bell core desired. A flanged 54 is provided on the core box to center the running box 48. The core box slidably supports the tapered locking key patterns 55 for the bell core. These key patterns 55 are mounted for radial sliding movement in the core box and crank handles 56 are provided for shifting the key patterns 55 back and forth, such handles 56 being provided with threaded shafts 57, which engage through threaded openings in portions 58 of the key patterns, the threaded shaft being held against longitudinal motion by the end collars 59, but, of course, being free to be rotated. The bottom or table 60 for the runner box is adapted to receive and support the same and is carried by the spider 61.

95 The supporting legs 62 for the core box are erected upon the bed plate 63 of the machine. This bed plate supports a hydraulic or other cylinder 64 having the plunger 65

therein coupled to the plunger rod 66 to which the spider 61 is affixed. The upper end of the plunger rod 66 moves in a guide sleeve 67. The guide sleeve 67 forms the hub 5 of the core box. The cover 68 of the cylinder 64 limits the upward travel of the piston 65. A dust cap 69 may be provided on the hub 67 of the core box.

Referring now to Figure 8, 70 designates 10 the hook ring being a part of the pattern drawing mechanism, while 71 designates the pattern hooks which are carried by the chains 72 and 73. Hold-down lugs 74 are welded or otherwise secured to the pattern hooks 71. 15 A wooden bridge 75 is provided with legs 76 which rest on the inside stripping plate 38. The bridge is adapted to receive vertical pressure from the lugs 74 as hereinafter described.

20 Referring to Figure 9, 77 designates a conventional compressed air jarring machine or jolter being shown placed in a pit 78 and projecting through the pit floor 79. The flask is shown as placed upon the jarring machine.

25 In Figure 10, 80 designates a turntable for receiving the flask. This turntable projects through the pit floor 81 and is caused to turn by electric motor power through appropriate gearing. 82 shows a ramming unit of a conventional sand throwing, molding and ramming machine, commonly known as a "sand slinger".

The turntable is provided in the pit with a ring gear 83 and on diametrically opposite 35 sides the ring gear is engaged by pinions 84 which are driven through reduction or other gearing 85 of a conventional form from separate electric motors 86. The purpose is to apply power to rotate the massive turntable

40 80 and its stupendous weight simultaneously at diametrically opposite points of the circle which avoids binding in the gearing, makes the task of rotation easier, and simpler, reduces wear in the parts, and the consumption 45 of electric current.

In the use of the device, referring to Figures 1 and 2, the casting stool 20 is carefully bored so that the openings for the pins 22 are equidistant from the center. In like manner the inner pins 23 for the arbor are also equi-distant from the center of the casting stool.

Care is also taken in the formation of the 55 cheek 24 to machine it so that it will be concentric and properly receive the pins 22, whereby such cheek 24 is accurately concentric with the casting stool. The core arbor 26 is also machined carefully and extends up to the bell line. Care must be taken to have 60 the arbor 26 concentric both with the casting stool 20 and with the flask or cheek 24. The wings 28 on the core arbor 26 are for the purpose of supporting the sand in the core and the arbor is preferably made with the barrel 65 tapered, and with the small end down to fa-

cilitate removal from the pipe. The sectional spigot key chill rings 34 are bolted to the upper surface of the casting stool 20, and are so centered that, when the spigot key chills 31 are in place, the inside curved surfaces of 70 the chills 31 form sections of a circle concentric with respect to the vertical axis of the casting stool and of the same radius as that of the outside of the pattern 29. The pockets 75 33 in the rings 34 will restrain the chills 31 from movement in a horizontal plane. As the sand is rammed down against the beveled upper portions of the chills 31, they are made to press closely against the pattern 29.

The cavities 32 in the chills form mold 80 cavities of the exact size and shape of the spigot locking keys desired.

The casting stool, cheek, core arbor, chill rings and chills, together with the centering pins make up a complete flask. When the 85 completed flasks are assembled, the cheeks 24 are clamped to the casting stools 20 for ease of handling by overhead cranes.

When the flask is being assembled for a size and weight pipe requiring bottom pouring of 90 the metal, dry sand gate cores 52 as shown in Figures 1 and 4 are placed in the pockets 21 in the casting stool 20, said cores being so placed that the small gate cavities 47, through which the metal is to enter the pattern cavity, 95 are concentric with and will be covered by the pattern during ramming of the sand. When the flask is assembled for a size and weight of pipe requiring top pouring, these pour gate cores 52 are omitted, and the casting stool 100 pockets 21 filled level full of sand, or a casting stool is used of the same form but with the gate core pockets eliminated.

The molding operation is started by placing a complete flask on the table of a molding machine. The pattern 29 is then lowered into the flask, being centered with respect to the flask and molding machine by the spigot key chills 31 and they in turn by the chill rings 34 fastened to the casting stool.

110 It has been found that certain sizes and weights of pipe may be made better when the tempered molding sand is rammed on a jarring machine or jolter such as shown in Figure 9. In this method, with the flask and pattern in place, together with the pattern for the gate 44 shown in Figure 4, when the mold is to be bottom poured, tempered molding sand is shoveled or spouted into the space between the cheek and pattern and into the 115 space between the core arbor and pattern. The conventional jarring machine or jolter is so made that when compressed air is allowed to flow into the machine, the piston and table attached thereto, together with the flask and sand, are caused to be jarred or jolted and the sand thereby rammed.

Certain other sizes and weights are better 120 molded by the sand slinger method shown in Figure 10. In this method the flask and 125 sand are caused to be jarred or jolted and the sand thereby rammed.

130

pattern are placed, as before, in a centered position on a turntable 80.

This table is driven through the reduction gears 85 by the electrical motors 86. The 5 table is thus caused to rotate and the flask and pattern are caused to rotate therewith true with the axis of rotation of the turn table. While the table, flask and pattern, are revolving, sand is thrown by the sand slinger 82 into 10 the space between the cheek and pattern and between the core arbor and pattern with such force that the sand is rammed to the density desired.

Either the bottom pour or top pour methods 15 of gating the mold may be used with either jolter or sand slinger method of ramming the sand in the flask.

Upon completion of the above filling and ramming of the flask mold, the sand outside 20 the pattern is leveled even with the top of the cheek 24 and the sand inside the pattern is leveled even with the top of the core arbor 26. The inside and outside stripping plates 37 and 38 are then put in place, the outside stripping 25 plate 37 being clamped to the cheek 24. The centering plug 39 is also put in place. It will be remembered that the outside of the plug 39 is tapered and the largest diameter is the same as the bore of the inside stripping plate 38.

30 As the pattern 29 is machined with inside and outside diameters concentric, and as the inside stripping plate 38 is machined with inside and outside diameters concentric, the largest outside diameter of the centering plug 39 must now be concentric with the outside diameter of the pattern 29.

The next operation is to remove the pattern from the flask mold.

Referring to Figure 8, the hook ring 70 is 40 adapted to receive a power lifting crane hook. The wooden bridge 75 is placed with its two legs resting on the inside stripping plate 38. The hooks 71 are engaged in the openings in the upper end of the pattern 29 and the lugs 74 rest upon the bridge 75. Lifting action by 45 the crane acting on ring 70, exerts an angular upward pull on the grab hooks 71. The lifting strain thereby exerts an inward circular force on the grab 50 hooks 71 around the center of the lower circular hook part as an axis. This circular force is resisted by the downward pressure of the lugs 74 against the bridge 75.

With this appliance the core and inside 55 stripping plate 38 are held down while the pattern is withdrawn a sufficient distance to break the static friction between the bore of the pattern and the sand of the core. By the time the pattern is lifted a sufficient distance to allow the lug 74 to clear the bridge 75 the

friction between the pattern bore and the core is so reduced that there is no possibility of this friction being enough to lift the core against gravity with the pattern as it is further withdrawn. 70

After the pattern 29 is completely removed from the mold, the stripping plates 37 and 38 are likewise removed. The centering plug 39 is, however, left in place. Being of massive design the centering plug 39 will not 75 move during any careful handling of the mold and will remain central with the pattern impression by virtue of its mass alone. The completed flask mold is removed from the molding machine and placed on the pouring floor ready to receive the combined bell core and pour basin 48. 80

This bell core and pour basin are formed separately from the flask in the machine shown in Figures 6 and 7. The core box is 85 machined to give the shape and size of the bell core desired and has recesses 87 machined in its upper surface to receive the bell locking key patterns 55.

This core box is shown in Figures 14, 15 90 and 16. The key patterns 55 are held in angular relation one with the other but are free to slide toward and away from the center of the core box. The projecting ends of these key patterns are machined to the size and shape of the bell locking keys desired. By rotating the cranks 56, through the threaded engagement of the shafts 57 with the lugs 58, the key patterns may be advanced or retracted and thus moved toward or away from the 100 center of the core box on radial lines. The outer surface of the inner ring of the core box is machined to fit the bore of the runner box 48, which in turn is bored to fit the largest 105 outside diameter of the centering plug 39. The runner box is made up as shown in Figures 11, 12 and 13 of an outer cast ring 88 and an inner cast ring 89 connected by means of steel bars 90 cast in place. The difference 110 in the elevations of the bottom-machined surfaces 91 and 92 of the runner box is the difference in elevation of the top and bottom of the bell core desired and the like difference in elevations of the top of cheek 24 and core 115 arbor 26.

The inside diameter 93 of the bottom flange of the runner box is bored to slidably fit the outside diameter of the inner ring 54 of the core box 53.

In the molding of the combined bell core 120 and pour basin, the bell key patterns 55, shown in Figures 6 and 7 are moved in by turning crank 56 until they project inside the core box 53 to the thickness of the keys desired, the core bottom plate being in its lowest 125 position, as shown in Figure 6.

The runner box 48 is centered by the inner ring 54 of the core box and is supported on its outer ring by the top of the core box 53 and on its inner ring by the platform or core 130

bottom ring 60. Tempered molding sand 49 is rammed in the runner box, the sand taking the shape of the bell core desired. Gates for either top or bottom pouring, as desired, are 5 molded in the runner box and the pour basin in the upper sand in the runner box is shaped to give the molten iron an unrestricted path of travel around to the gates evenly. After ramming the sand, the key patterns 55 are drawn 10 back by means of the cranks 56 to the position shown in Figure 7 leaving impressions 50 in the bell core to make the bell locking keys. Compressed air is admitted beneath the piston 65, raising the piston, the rod 66, 15 the core bottom plate 60 and the combination bell core and pour basin, as shown in Figure 7.

This combination bell core and pour basin is now ready to be placed on the completed 20 flasked mold hereinbefore described.

After removal of the completed bell core, the core bottom plate is lowered by gravity upon the release of the compressed air under the piston 65, thereby completing the molding 25 cycle of the combined bell core and pour basin.

The combined bell core and pouring basin, as molded in the runner box 48, is now placed in the completed flask mold, being centralized 30 as it is lowered therein by the centering plug 39, thus completing a bell mold of even thickness. The completed pipe mold is now ready for pouring.

After pouring, the runner box 48 is removed and returned to the bell core molding machine, the core arbor 26 is removed ready to be cleaned and replaced on any casting stool 20; the cheek 24 is removed ready to be cleaned and replaced on any casting stool 20, 40 the pipe casting is removed for cleaning and finishing, the spigot key chills and chill ring, and casting stool are cleaned, and the molding sand retempered ready for the making of another mold.

45 It will be noted that in all description of parts and through the explanation of the assembly of the several parts to make up the complete mold, particular emphasis has been placed on the fixed relativity of all component parts to a common vertical axis. This common relativity assures that all parts of the mold cavity, and therefore all parts of the completed pipe, are concentric, and that 50 the pipe as cast is even in thickness throughout.

Referring to Figures 15 and 16 it is to be understood that the bottoms of the cavities 18 are tapered. Furthermore, the bell core 55 locking key patterns and the keys are also tapered.

It is obvious that various changes and modifications may be made in the details of construction and design of the above specifically 60 described embodiment of this invention with-

out departing from the spirit thereof, such changes and modifications being restricted only by the scope of the following claims:—

What is claimed is:

1. The herein described method for the manufacture of cast-iron pipe which consists in compacting green sand on opposite sides of a pattern in a mold flask, stripping the pattern from the flask, in a separate operation compacting green sand in a runner box to 70 form a combined bell core and pouring basin, assembly and centering the runner box upon the mold flask after removal of the pattern, and pouring the molten metal into the pour basin. 75

2. The herein described method for the manufacture of cast-iron pipe, which consists in compacting green sand on both sides of a pattern in a mold flask with the bell end of the pattern up and the spigot end down, stripping the pattern from the sand to leave a pipe moulding cavity, forming in a separate operation in a runner box a combined bell core and pour basin out of green sand, subsequently placing said runner box upon the top of the mold flask, and pouring the molten metal in the pour basin while the mold remains in upright position. 80

3. The herein described method for the manufacture of cast-iron pipe, which consists in centering a pattern in a mold flask, compacting green sand upon opposite sides of the pattern, centering a centering device from said pattern, stripping the pattern from the sand to produce a pipe moulding cavity, separately forming of green sand a combined bell core and pour basin, assembling said bell core and pour basin upon the top of the mold centered by the centering device with reference to the mold cavity, and pouring the molten metal in the pour basin and thence into the mold cavity. 90

4. The herein described method for the manufacture of cast-iron pipe, which consists in centering a pattern within a mold flask, compacting green sand upon opposite sides of said pattern, centering a runner box centering device from said pattern, stripping the pattern from the green sand to form a pipe moulding cavity, separately forming out of green sand in a runner box a combined pour basin and bell core, placing the bell core on top of the mold centered by the centering device with respect to the mold cavity, and pouring the metal into the pour basin and thence into the mold cavity in the vertical original upright position of the mold flask. 100

5. The herein described method for the manufacture of cast-iron pipe, which consists in centering a pattern in a mold flask with bell end up, compacting green sand upon opposite sides of said pattern, centering a runner box centering device from said pattern, stripping the pattern from the sand to form a pipe moulding cavity, forming in a 110

separate operation in a runner box a combined bell core and pour basin wholly out of green sand, placing the runner box upon the mold flask guided and centered by said centering device whereby the bell core will accurately take up its position with reference to the mold cavity, and pouring the molten metal in the pour basin in the original vertical upright position of the mold flask.
